UNITED STATES PATENT OFFICE.

WALTER E. COPITHORN, OF NATICK, MASSACHUSETTS.

DEMOUNTABLE RIM FOR PNEUMATIC TIRES.

1,100,472.

Specification of Letters Patent. Patented June 16, 1914.

Application filed February 8, 1912. Serial No. 676,233.

To all whom it may concern:

Be it known that I, WALTER E. COPITHORN, a citizen of the United States, residing at Natick, county of Middlesex, State of Massachusetts, have invented an Improvement in Demountable Rims for Pneumatic Tires, of which the following description, in connection with the accompanying drawing, is a specification, like characters on the drawing representing like parts.

This invention relates to demountable rims for pneumatic tires and it has for its object to provide a novel and simple device for holding and locking the demountable rim in place on the wheel.

The features wherein my invention resides will be more fully hereinafter described and then pointed out in the appended claims.

Referring to the drawings wherein I have illustrated some preferred embodiments of my invention, Figure 1 is a side view of a wheel having my improvements applied thereto; Fig. 2 is an enlarged section on the line $x-x$, Fig. 1; Fig. 3 is an enlarged section on the line $y-y$, Fig. 1; Fig. 4 is an enlarged fragmentary view showing the manner in which the locking ring is applied to the wheel; Fig. 5 is a side view of the one-piece locking ring removed; Fig. 6 is a fragmentary view showing the operation of the cone member in the slot 18; Fig. 7 is a view similar to Fig. 1 showing my invention embodied in a two-part locking ring; Fig. 8 is a view of one of the sections of the two-part locking ring; Fig. 9 is a view of the other section of said locking ring; Fig. 10 is an enlarged section on the line $a-a$, Fig. 7; Fig. 11 is a section on the line $b-b$, Fig. 7; Fig. 12 shows my invention applied to a solid rubber tire; Fig. 13 is a section on the line $c-c$, Fig. 12; Fig. 14 is a section on the line $d-d$, Fig. 13.

1 designates the body of a wheel which may have any suitable or usual construction and which is provided with the usual felly 2.

I have shown herein my invention as embodied in a demountable rim for pneumatic tires and also a demountable rim for solid rubber tires.

Referring first to the pneumatic tire construction, 3 designates a demountable rim adapted to sustain the pneumatic tire 4. This rim and tire may have any suitable or usual construction, that herein shown being of the well-known clincher type. The par-

ticular form of the tire and demountable rim, however, does not enter into the invention.

The felly 2 has secured to one side thereof a positioning ring 5 which is provided with a positioning flange 6 that is adapted to engage the demountable rim and position the latter on the felly. 60

7 designates a ring which is secured to the opposite side of the felly, said ring being herein shown as provided with the inturned flange 8 which occupies a rabbet formed in the felly 2. The positioning ring 5 and the ring 7 may be permanently secured to the tire in any suitable way. I have herein shown for this purpose bolts 9 which pass through the felly and which have heads 10 to engage the ring 7, and which are provided with nuts 11 to engage the positioning 70 ring 5. The positioning ring 5 and the ring 7 are intended to be permanently fastened to the felly 2. 75

The demountable rim 3 is held in position by a locking ring 12 which may either be a one-piece ring or may be made in two parts, as desired, and which has locking engagement with the heads 13 of studs 14 that are secured to and extend laterally from the felly 2. These studs 14 may be secured in 85 place in any suitable way. In the embodiment of the invention shown in Figs. 1 to 6 said studs are formed as part of the bolts 9, that is, each bolt is provided with an extension beyond the head 10, which extension is shaped to present a stud 14 having a head 13. The locking ring shown in Fig. 1 is a 90 one-piece locking ring and it is provided with a body portion which overlies the ring 7 and with a flange portion 15 which engages the demountable rim 3. The one-piece locking ring is shown in Fig. 5, and it 95

is provided with a plurality of slots 16, one for each of the headed studs. Said slots have a progressively-decreasing width from one end to the other, and at their widest end they are of a size to permit the heads 13 of the studs to pass through them, as shown in Fig. 4.

In applying the locking ring it is placed 105 over the studs with the heads 13 thereof passing through the wide ends of the slots and after the ring is in place it is given a movement in the direction of the length of the slots to carry the narrow ends of the 110 slots behind the heads, as shown in dotted lines Fig. 4. When the locking ring is in

this position the portion 17 thereof on each side of the narrow end of the slot lies behind the head 13 so that the ring is firmly held in place. This movement of the locking ring into its operative position is provided for by means of a wedge member which is herein shown as in the form of a cone acting in a tapered slot 18 formed in the ring and tapering in the opposite direction from the slots 16. The cone member is shown at 19 and is in the form of a nut which is screw-threaded onto a bolt 20 that is anchored in the felly 2. When the locking ring 12 is first placed over the headed studs, the bolt 20 occupies the narrow end of the slot 18, as shown in Fig. 6. As the cone member 19 is screwed onto the bolt and the cone enters the slot 18 it forces the locking ring around into its locking position shown in Figs. 1 and 4, as will be obvious. Said cone, therefore, not only moves the locking ring into its locking position, but it also holds it in such position.

The removal of the demountable rim 3 involves merely unscrewing the cone-shaped nut 19 and then shifting the locking member 12 so as to bring the heads 13 opposite the large portion of the slots and then moving the locking ring laterally. The placing of the locking ring in position involves merely inserting it over the headed studs and then screwing the cone-shaped nut 19 into place.

Instead of making the locking ring in one piece, as shown in Fig. 5, I may make it in two parts, as shown in Figs. 7 to 11, inclusive. In this embodiment the two parts of the locking ring are designated 21, 22, each being substantially semi-circular in shape. Each is provided with the tapered slots 16 adapted to fit over the headed studs 14, as above described. One end of each of the rings is provided with a notch 25 to enter behind the head 23 of a stud 24 which is secured to the felly in any suitable way, preferably by being formed on the end of one of the clamping bolts 9. At the other ends the sections of the locking ring overlap each other and the section 22 is provided with a slot 26, while the section 21 is provided with a tapered slot 27 which tapers in the opposite direction from the slots 16, and the larger end of which is beveled, as shown at 28. In applying this sectional locking ring to the wheel the two sections are placed in position over the headed studs 13 with the notches 25 in the ends thereof situated to enter behind the head 23 and with the end of the bolt 20 passing through the slots 26, 27. The cone-shaped nut 19 is then screwed onto the bolt 20 and as it enters the tapered slot 27 it forces the section 21 in the direction of its length to cause the narrow ends of the slots to enter behind the heads 13. During the forward movement of the nut 19 the small end thereof enters the slot

26 and engages the end 29 thereof and forces the ring section 22 longitudinally thereby to lock said ring behind the heads of the studs. The cone 19, together with the headed studs 14, serves to firmly hold the locking ring sections in place and the locking ring sections hold the demountable rim in position. I have shown herein additional rivets or bolts 31 near the outer edge of the rings 5 and 7 for securing them to the felly.

My invention may also be applied to a demountable rim constructed to sustain a solid rubber tire, as shown in Figs. 12 and 13. In this embodiment of the invention the hard rubber tire is shown at 32 and it is secured to a demountable rim 33 in some suitable way. The manner of connecting the tire to the rim may be varied without departing from the invention. As illustrating one construction I have shown said tire as having a wire 34 embedded therein, which wire is connected to the rim 33 by eye-bolts 35 arranged with the wire 34 passing through the eyes, said bolts passing through the rim 33 and being connected thereto by nuts 36. In the embodiment shown in Figs. 12 and 13 the felly 2 has secured to one side thereof a positioning ring 37 which is provided with a flange 38 to engage the rim 33 and the side of the tire and on the opposite side is a clamping ring 39 similar in shape to the ring 37, but removably held in place. The clamping ring 39 is held in position by a locking ring 40 which may either be a one-piece locking ring or a two-piece locking ring, as desired. This locking ring is provided with the tapered slots 16 as described above and these slots are adapted to enter over and be held behind the heads 42 of studs 41 which are secured to the felly 2 in some suitable way. I have herein shown said studs 41 as being formed integral with bolts 43 which are fastened to the felly band 44 and are situated exterior thereto, said bolts 43 extending through the positioning ring 37 and being shown as riveted to the felly band by rivets 45.

46 designates bolts or rivets which extend through the felly 2 and the positioning ring 37 and serve to permanently connect the two parts. In this embodiment the demountable rim 33 is sufficiently larger than the felly band 44 to provide the necessary space to receive the bolts 43. The locking ring 40 is held in place by a tapered nut 19 screw-threaded onto a bolt 20, as above described, and if the locking ring 40 is a one-piece ring, said nut operates in a tapered slot 18 formed in the locking ring, as shown in Fig. 12, while if the locking ring 40 is a two-piece ring, then it will have the construction shown in Figs. 8 and 9.

I have herein shown the slots 16 which are formed in the locking ring as being closed slots, but this particular construction is not

necessary as the slots are primarily openings to receive the heads of the studs and the locking ring has such a shape adjacent these openings that when said ring is turned annularly, portions of the ring pass behind the heads of the studs, thus locking the ring in place. Where the ring is made of one piece it is moved annularly as an entity to bring it into locking position. Where the locking ring is made in two sections, each section has a separate movement, but the movement of each section is annularly so that by the term "annular movement of the locking ring" I mean a movement annularly whether the locking ring is made in one section or two.

It will be obvious that various changes may be made in the constructional features of the invention without departing therefrom.

Having fully described my invention, what I claim as new and desire to secure by Letters Patent is:

1. In a wheel, the combination with a wheel body having a felly, of headed studs extending laterally from one side thereof, a demountable rim encircling the felly, a locking ring for locking said demountable rim in place, said locking ring having slots wider at one end than at the other, said slots at their widest ends having a sufficient width to pass over the heads of the studs, and a cone nut co-acting with said locking ring to force it positively in the direction of the length of the slots thereby to bring the narrow portion of said slots behind the heads.

2. The combination with a wheel body having a felly, of headed studs extending laterally from one side thereof, a demountable rim encircling the felly, a locking ring having slots of progressively decreasing width from one end to the other, said slots at their widest ends having a sufficient width to pass over the heads of the studs, said ring also having another tapered slot which tapers in the opposite direction from the first-named slots, and a wedge member to enter said latter slot and move the ring into its locking position.

3. In a wheel, the combination with a

wheel body having a felly, of a rim-positioning ring secured to one side thereof, bolts extending transversely of said felly for securing said ring to the felly, said bolts presenting at one end headed studs which extend laterally from the felly, a demountable rim encircling the felly, a locking ring for said demountable rim adapted to have locking engagement with said headed studs, said locking ring having a cone-receiving slot of progressively-varying width, a bolt extending transversely through the felly and said latter slot, a cone-shaped nut screw-threaded onto the bolt and entering said slot thereby to cause said locking ring to move in the direction of the length of the slots therein so as to bring the narrow portions of said slots behind said heads.

4. In a wheel, the combination with a wheel body having a felly, of a rim-positioning ring overlying one side of the felly, bolts extending transversely of said felly and ring for securing the latter to the felly, said bolts presenting at one end headed studs which extend laterally from the opposite side of the felly, a demountable rim encircling the felly and engaging the rim-positioning ring, and a locking ring for said demountable rim, said locking ring having slots of progressively-decreasing width from one end to the other, said slots at their widest ends having a sufficient width to pass over the heads of the studs, and said locking ring also having a cone-receiving slot of progressively-varying width, a bolt extending transversely through the felly and said latter slot, and a cone-shaped nut screw-threaded on said bolt and entering said slot thereby to cause the locking ring to be moved in the direction of the length of the slots therein and to be brought into locking engagement with the headed studs.

In testimony whereof, I have signed my name to this specification, in the presence of two subscribing witnesses.

WALTER E. COPITHORN.
